UNITED STATES PATENT OFFICE.

WILHELM PAPE, OF CHARLOTTENBURG, GERMANY, ASSIGNOR TO GENERAL ELECTRIC COMPANY, A CORPORATION OF NEW YORK.

STEAM-REGULATOR FOR TURBINES.

1,085,156.

Specification of Letters Patent. Patented Jan. 27, 1914.

Application filed January 21, 1913. Serial No. 743,335.

To all whom it may concern:

Be it known that I, WILHELM PAPE, a subject of the King of Prussia, residing at Charlottenburg, Germany, have invented certain new and useful Improvements in Steam-Regulators for Turbines, of which the following is a specification.

This invention relates to tapped turbines, in which a portion of the motive fluid is led off to a heating or other industrial system after giving up a portion of its energy in the high pressure stage or stages of the machine. In such turbines, the most advantageous condition as regards steam consumption is attained if the cross-sectional areas of the bucket spaces for the low pressure part of the machine are calculated for full load operation. Now when such a turbine is under full load and the heating or other industrial system is taking very little steam, or is wholly shut off, then the overflow valve between the extraction chamber and the low pressure part of the turbine will stand entirely open, so that the low pressure bucket wheels are getting motive fluid at the same pressure as prevails in the extraction chamber.

It is desirable to maintain the pressure in the heating system at a constant figure, and from this condition it follows that when the overflow valve is wide open only a certain amount of steam will flow to the low pressure wheels, and thus the energy delivered by the low pressure end does not vary. Now in case of an overload on the turbine there is no way to carry it unless the high pressure admission valve is opened wider to supply a greater quantity of motive fluid, and this will increase the pressure in the low pressure end, but at the same time it will increase the pressure in the extraction chamber, and therefore the amount of steam passing to the heating system, which is undesirable.

The present invention aims to make it possible to carry an overload quite independently of the amount of steam extracted by the heating system.

In the accompanying drawing Figure 1 shows diagrammatically a longitudinal section of a tapped turbine embodying my invention, and Fig. 2 shows a modification.

High pressure steam is admitted at 1 to the high pressure bucket wheel 2, from

3 from which it can be drawn off by the conduit 4 to supply a heating or other industrial system. An automatically opening main overflow valve 5 responsive to pressure changes permits the surplus steam, if any, to pass to the low pressure portion of the turbine, where it acts upon the groups of bucket wheels 6, 7. It will be noted that wheel 2 forms the high pressure element, wheels 6 what may be termed the intermediate pressure element and wheels 7 the low pressure element.

In working with a certain amount of steam passing to the heating system, the turbine may become loaded to such an extent that the valve 5 will be wide open, and thus the maximum amount of steam will pass to the low pressure end of the machine. In order, therefore, to enable the machine to carry an overload under these circumstances, without increasing the amount of steam passing to the heating system, an auxiliary overflow valve 8 is provided, responsive directly or indirectly to the increase in steam pressure in the extraction chamber, and arranged to admit steam from said chamber to a later stage of the low pressure portion of the turbine; say to the group of bucket wheels 7, where the bucket spaces are larger and hence can pass more steam. This produces a greater flow of motive fluid through the turbine, without influencing the amount passing off to the heating system, and because of this increased flow the power furnished by the turbine is correspondingly increased. Although the last group of wheels 7 are thus subjected to a higher pressure than when the valve 8 was closed, yet the available power is not entirely in accordance with this increased pressure, because the first group 6 is subjected to more or less back pressure. The steam will divide between the two groups in proportion to the resistance of the passages of the first three groups of wheels and that of the pipe leading to the valve 8 and the amount of opening of the latter.

The valve 5 is preferably operated by a motor comprising a piston 9 working in a cylinder 10 and connected to the stem of the valve. A pilot valve 11 controls the admission and exhaust of motive liquid for said motor and is itself actuated by a pressure responsive device, such as a movable abutment 12 exposed on its upper side to the pressure.

in the extraction chamber by the pipe 13 running from the extraction chamber or the conduit 4. A spring 14 opposes the fluid pressure acting on said abutment. A lever 5 15 communicates the movements of said abutment to the pilot valve, and is pivotally connected to the stem of the valve 5 to function as a follow-up device.

Any suitable means may be adopted for 10 causing the opening of the valve 8 when the speed governor admits the increased amount of steam to the machine. In Fig. 1 there is shown a motor 16 similar to the one which operates the valve 5 and controlled by 15 the pressure in the extraction chamber through the pipe 17 and pressure responsive device 18. This device is adjusted to yield to a higher pressure than device 12. The result is that the valve 5 will be entirely 20 opened before the device 18 will open the by-pass valve 8. In the modification shown in Fig. 2 the by-pass valve 8 is arranged as a slide valve upon the stem of the valve 5; that is to say, the valve is loose upon said 25 stem and does not open until the collar 19 on said stem strikes it. This action does not take place until the valve 5 is wide open.

In accordance with the provisions of the patent statutes, I have described the principle of operation of my invention, together 30 with the apparatus which I now consider to represent the best embodiment thereof; but I desire to have it understood that the apparatus shown is only illustrative, and that the 35 invention can be carried out by other means.

What I claim as new and desire to secure by Letters Patent of the United States is:—

1. The combination with a tapped turbine having a main overflow valve for admitting 40 steam to the low pressure end of the machine, of an auxiliary overflow valve for admitting steam from the extraction chamber directly to a lower stage of the low pressure end in order to avoid disturbing the pressure 45 in the heating system when an overload

comes on with the main overflow valve wide open.

2. The combination with a tapped turbine having a main overflow valve for admitting steam to the low pressure end of the machine, of an auxiliary overflow valve responsive to pressure in the extraction chamber and operating to admit steam from said chamber to a lower stage of the low pressure end when an abnormal amount of steam is 55 admitted to said chamber by reason of an overload on the turbine.

3. The combination with a tapped turbine having a main overflow valve for admitting steam to the low pressure end of the machine, and an auxiliary overflow valve for bypassing the steam around a portion of the low pressure wheels, said latter valve opening only after the main overflow valve has become wide open.

4. The combination with a tapped turbine having a main overflow valve for admitting steam to the low pressure end of the machine, an auxiliary overflow valve for bypassing the steam around a portion of the low pressure wheels, and means responsive to pressure changes in the extraction chamber for actuating said valves in succession.

5. The combination with a tapped turbine having a main overflow valve for admitting steam to the low pressure end of said turbine, an auxiliary overflow valve for bypassing the steam around a portion of the low pressure wheels, a motor for operating each valve, a pilot valve for said motor, and 75 a movable abutment connected to said pilot valve and exposed to the fluid pressure in the extraction chamber.

In witness whereof, I have hereunto set my hand this 31st day of December 1912.

WILHELM PAPE.
